UNITED STATES PATENT OFFICE.

PERLEY L. KIMBALL, OF BELLows FALLS, VERMONT, ASSIGNOR TO THE VERMONT FARM MACHINE COMPANY, OF BELLows FALLS, VERMONT, A CORPORATION OF VERMONT.

CREAM-CONE FOR CREAM-SEPARATORS.

1,247,965.

Specification of Letters Patent. Patented Nov. 27, 1917.

Application filed September 28, 1917. Serial No. 193,801.

To all whom it may concern:

Be it known that I, PERLEY L. KIMBALL, a citizen of the United States, residing at Bellows Falls, in the county of Windham and State of Vermont, have invented a certain new and useful Improvement in Cream-Cones for Cream-Separators, of which the following is a full, clear, and exact description.

10 The object of this invention is to provide an efficient means for regulating the density of the cream produced by a centrifugal cream separator of the cone or disk variety of liner or skimmer.

15 The invention consists of a cream cone having a constricted or contracted neck provided with a vertically arranged pocket, the effective area of which is variable by means of a horizontally arranged adjustable screw plug, above which is a lateral opening communicating with the pocket and the exterior space for the discharge of the cream, as I will proceed now to explain and finally claim.

20 In the accompanying drawings illustrating the invention, in the several figures of which like parts are similarly designated, Figure 1 is a vertical section of a cone and part of a cover of approved construction, 30 the cone containing one form of the invention. Fig. 2 is a cross-section of the neck of the cone of Fig. 1, taken at right angles to the section in that figure. Fig. 3 is a top plan view of portions of Fig. 1. Fig. 4 is a top plan view and Fig. 5 is a side elevation illustrating a modification.

25 The cover 1 and the body of the cone 2 may be of any usual, approved or preferred construction. The cone 2 has a neck 3, the upper internal diameter of which is constricted or contracted in any suitable way, as by a ring 4 applied thereto in any suitable permanent and immovable way and of a thickness suitable to receive a vertically 35 disposed recess 5 extending from its bottom nearly to its top. This recess is in the form of an inverted pocket, and is herein referred to as a pocket, it being closed at its top by a solid portion 6 of the ring 4 and open at its bottom, as clearly shown in Figs. 1 and 2, thus forming a cream passage capped or closed at its top. Near the bottom of the pocket is a horizontal or lateral screw-threaded hole 7 in which is placed the solid 45 cream regulating screw plug 8. This screw

50 plug may be turned so as to close the pocket more or less fully in order to control the density of the cream. A horizontal hole 9 is arranged in the neck above the screw plug and communicates with the pocket and the exterior of the neck, for the passage of the cream. The neck of the cone may be provided, in alinement with the pocket, with a block 10 made with or permanently and immovably fixed to the neck and standing off laterally therefrom sufficiently to fill, fully or otherwise, the vertical slot 11 in the neck 12 of the cover and flush with the periphery of the neck, as shown in Figs. 1 and 3, or so as to project laterally beyond it as seen in Figs. 4 and 5. This block has in it continuations of the screwthreaded hole for the regulating screw plug and the cream exit. The block projects as far from the center of the bowl as the neck of the bowl is from the center, and preferably slightly more, so that the cream shall discharge at a little larger circle than the neck of the bowl or cover and thereby in no way interfere with its escape into the cream pan free from the neck of the bowl or cover.

55 As will be understood the internal diameter of the ring 4 is substantially equal to the external diameter of the feed tube used in the separator, and this tube forms the inner wall of the pocket 5.

60 By the construction described, the vertical cream passage (pocket 5) has its top capped or closed above the regulating screw plug, thereby forming a small reservoir or pocket above and also outside of the inner end of the screw plug, so that the passage of the cream may be regulated with great nicety. The pocket functions as an open space or pool, into which the cream that 65 has been regulated by the inner point of the screw may be discharged and thence flow outward through the outlet 9 into the receptacle outside.

65 Another important feature of the invention is the provision of a pocket which extends beyond the inner end of the screw plug and communicates with a cream outlet or exit arranged above such plug. This space or pocket is of such capacity that 70 when the screw 7 is turned away from the center, there is still left enough capacity for the overflow of cream that has been 75 regulated. It will be noticed that as the screw approaches the center of the neck or 80

recedes from it the holding capacity of this pocket back of the screw varies, but there is room enough for any adjustment that the screw is capable of performing.

- 5 Another feature of the invention is the provision of the extension-block or boss 10 made as a fixed part of the neck of the cone, the combined thickness of the neck and block being sufficient to bring the outside 10 face of the block even or flush with the neck of the cover or to extend beyond it, the cream outlet leading from said pocket through the neck and block as an integer to an exit that is beyond the outer wall of 15 the neck of the cover.

The advantage of having the extension-block or boss 10 made so that it is integral is that its inner or extreme outer surface is such that its outer passage shall not be 20 carried through different thicknesses of separate concentric necks, one sliding inside of the other, as is the case with some makes of cream regulating devices which have been on the market for some time. In such 25 devices the holes in the different parts as these are assembled, are supposed to come in exact alinement, but due to inaccuracies in drilling the holes in the different parts, and after they are worn, these holes do not 30 exactly aline one with the other. There is an offset or corner, and there is a ridge of 35 cream between the walls due to this inaccuracy of alinement. With the boss or extension block of the present invention, the passage is solid all the way through, and there is no chance for non-alinement or leaky joints.

Variations in details of construction are considered as within the scope and principle of the invention.

What I claim is:—

1. A cream cone for centrifugal cream separators, having a neck provided with a ring having a vertical pocket closed at its 45 top, an extension block arranged on the outside of the neck in alinement with the pocket, a screw plug arranged in a screw-threaded hole in the block and neck and adapted to be projected more or less into

the pocket, and a cream outlet passage also 50 extending through the block and neck and into the pocket above the screw plug.

2. A cream cone for centrifugal cream separators, having a neck provided with an interior ring, said ring having a vertically 55 arranged recess closed at its top and open at its bottom, and a screw plug arranged horizontally in the neck near the bottom of the recess and adapted to be projected into the recess to restrict its effective area 60 for the passage of the outgoing cream without altering the capacity of the upper portion of the recess, said recess provided near its upper end with a cream exit.

3. A cream cone for centrifugal cream 65 separators, having a contracted neck provided with a recess closed at its upper end and open at its bottom, a laterally extending block on the outside of the neck in alinement with the recess and provided with a cream exit extending through it and into the closed end of the recess, and a screw plug arranged in a hole extending horizontally through the block and neck 70 and into the recess below the cream exit. 75

4. A cream cone for centrifugal cream separators, having a contracted neck provided with a recess closed at its upper end and open at its bottom, a laterally extending block on the outside of the neck in alinement with the recess and provided with a cream exit extending through it and into the closed end of the recess, and a screw plug arranged in a hole extending horizontally through the block and neck 80 and into the recess below the cream exit, combined with a cover having a neck provided with a slot into which the block extends so as to deliver the cream free of the neck. 85

In testimony whereof I have hereunto set my hand this 26th day of September, A. D. 1917.

PERLEY L. KIMBALL.
